UNITED STATES PATENT OFFICE.

VICTOR E. MERTZ, OF NEW YORK, N. Y.

AIR-CIRCULATING SYSTEM.

1,170,308.

Specification of Letters Patent.

Patented Feb. 1, 1916.

Application filed March 3, 1915. Serial No. 11,804.

To all whom it may concern:

Be it known that I, VICTOR E. MERTZ, a citizen of Switzerland, residing at New York, in the county of New York and State 5 of New York, have invented new and useful Improvements in Air-Circulating Systems, of which the following is a specification.

This invention relates to apparatus for humefying air as it is admitted into a building and it consists in the novel features hereinafter described and claimed.

An object of the invention is to provide a humefying apparatus of simple and durable structural arrangement having its parts so 15 assembled that they may be readily adjusted to increase or diminish the humid condition of the air breathed.

With the above object in view the apparatus includes a pipe which leads in through 20 the wall of a building from the exterior thereof and which is provided at the opposite sides of the said walls with doors or valves adapted to regulate the quantity of air admitted into the said pipes. Spraying 25 devices are located in the pipe and are adapted to spray the humidity into the air in the form of sprays or very fine particles. A draining drum is connected with the said pipe and means is provided in the said drum 30 for separating condensation and larger particles of moisture from the air and a delivery pipe is connected with the said drum. Said delivery pipe gradually decreases in diameter from the drum and is provided at intervals 35 along its side with cone-shaped nozzles through which the humefied air is liberated within the building. A sieve is adjustably mounted in the inner end of the delivery pipe and may be projected more or 40 less into the draining drum to increase or diminish the volume of the flow of air through the delivery pipe.

It is to be understood that while the apparatus is primarily designed to be used for 45 the purpose of humefying air it may also be used for the purpose of sterilizing the same. The apparatus may also be used for the purpose of deodorizing air or for imparting a particular odor or scent to the same.

50 In the accompanying drawing:—Figure 1 is a side elevation of the apparatus. Fig. 2 is a longitudinal sectional view of the same. Fig. 3 is a transverse sectional view of the same, cut on the line 3—3 of Fig. 2.

55 The apparatus comprises a pipe 1 which passes through a wall 2 and air is conducted

through the pipe 1 from the exterior of the building of which the wall 2 forms a part to the interior thereof. The pipe 1 is provided at its end beyond the outer side of the wall 2 60 with a hinged door or valve 3 which may completely close the end of the said pipe or may be positioned to regulate the flow of air through the pipe 1. The pipe 1 is provided at a point within the wall 2 with an 65 opening 4 at the edge of which is hinged a door or valve 5. The said door 5 may completely close the opening 4 or may be swung away from the said opening to any desired degree, thereby regulating the quantity of 70 air which may enter the pipe 1 through the opening 4.

Spraying nozzles 6 are located in the pipe 1 and preferably arranged concentric therewith as shown in Fig. 2 of the drawing. A 75 liquid supply pipe 7 is connected with the nozzles 6. A draining drum 8 is connected with the inner end of the pipe 1 and is preferably conical in shape as shown in Figs. 1 and 2 of the drawing. A drain pipe 9 is 80 connected with the drum 8 approximately at the lowest point thereof and through the said pipe 9 liquid may be drawn from the drum 8.

An air outlet pipe 10 is connected with 85 the drum 8 at the end thereof opposite the end with which the pipe 1 is connected and the said outlet pipe 10 is in longitudinal alinement with the pipe 1. The pipe 10 gradually decreases in diameter from the 90 drum 8 toward the end of the said pipe which is the more remote from the drum and the pipe 8 is provided at intervals along its length with cone-shaped nozzles 11 through which the air from the pipe 10 may be admitted into the interior of a building.

A sieve 12 is movably mounted in the inner end of the pipe 10 and may be projected into the drum 8 as shown in Fig. 2 of the drawing. The said sieve is provided with a 100 pin 13 which passes through a slot 14 disposed longitudinally in the pipe 10. By adjusting the pin 13 along the slot 14 the sieve 12 may be moved in the pipe 10 and extended to a greater or less degree in the 105 drum 8 and as the openings at the sides of the sieve 12 are uncovered the transverse sectional area of the admission end of the pipe 10 is increased; consequently means is provided for increasing or diminishing the 110 quantity of air which may be permitted to pass through the pipe 10. Two sets of de-

flector plates 15 are pivotally mounted within the drum 8 for swinging movement upon horizontal pivots 16 and the free edges of each set of plates 15 are connected together by means of a rod 17. The rods 17 pass through the sides of the drum 8 and are provided at their outer ends with handles 18 which may be used for moving the rods 17 longitudinally whereby the plates 15 may be 5 swung and positioned at a desired angle. A set of deflector plates 19 are pivotally mounted in the drum 8 between the sets of plates 15 and are adapted to swing upon vertically disposed pivots 20. A rod 21 connects the free edge portions of the plates 19 together and passes through the side of the drum 8 and is provided at its outer end with a handle 22. The handle 22 may be used for moving the rod 21 longitudinally whereby 10 the plates 19 may be swung upon their pivots consequently the plates 20 may be positioned at desired angles with relation to vertical planes passing through the pivots 20.

The operation of the apparatus is as follows: Assuming that one or both of the doors 3 and 5 have been opened to a desired extent and a liquid is forced through the pipe 7 and nozzles 6 into the pipe 1, the passage of the said liquid from the nozzles 30 6 through the pipe in the direction of the drum 8 creates a partial vacuum in the pipe 1 which draws the air in through the opening 4, or if the said opening is closed through the end of the pipe which is normally closed by the door 3. This air follows the sprays from the nozzles 6 and when it arrives at the nozzles it takes up the spray and consequently the air is humefied. Should the air absorb an excessive amount 35 of moisture the said moisture will condense or collect upon the plates 15 and 19 as the current of air passes between the said plates and from the said plates the moisture will drip to the lower side of the drum 8 and 40 45 gravitate into the pipe 9 through which it is led out of the said drum 8.

By varying the angle of inclination of the plates 16 and 19 the passage of the air through the drum 8 may be checked more or less and consequently greater or less opportunity may be afforded for the moisture to condense upon the said plates. That is to say if an extremely moist air is desired the plates 15 and 19 are positioned as to offer 50 55 the least resistance to the passage of the air through the drum 8 but if a volume of air moist to a slight degree only is desired the plates 15 and 19 are positioned to cause the current of air to move in tortuous paths 60 while passing the plates, thus prolonging the time required for the air to pass the plates and permitting the moisture to condense or collect thereon.

After leaving the innermost set of plates 65 15 the current of air is forced through the

openings of the sieve 12 into the pipe 10 and along the said pipe and out through the nozzles 11. By reason of the fact that the pipe 10 gradually decreases in diameter from the drum 8 the air will move at the uniform rate of speed through the pipe 10 notwithstanding that some of it escapes in the vicinity of the drum 8 and furthermore the air in the pipe 10 will be maintained throughout the length of the pipe approximately at a uniform degree of compression. 70 75

When it is desired to use the apparatus for the purpose of sterilizing the air a sterilizing agent is applied to the water which is permitted to enter the pipe 1 through the pipe 7 and the nozzle 6. Likewise when it is desired to deodorize the air a deodorant is applied to the said liquid and if it is desired to scent the air a perfuming agent is applied to the said liquid. 80 85

Inasmuch as the plates 15 and 19 are in cruciform relation the current of air which passes through the drum 8 is divided into a number of relatively fine streams and as the said plates cleave the current into the streams a maximum amount of surface is presented to the streams and upon these surfaces the condensation hereinbefore described may the more readily take place. 90

From the above description taken in conjunction with the accompanying drawing it will be seen that simple and durable means is provided for humefying air and that the parts may be easily and quickly adjusted to regulate the quantity of air passing through the apparatus and also to regulate the degree to which the said air is humefied. Furthermore the apparatus may be employed for the purpose of sterilizing air admitted into a building and also for the purpose of deodorizing or imparting a scent or perfume to the air. 95 100 105

Having described the invention what is claimed is:—

1. A humefier comprising a pipe adapted to direct a draft of air, means for injecting moisture into the same, a drum connected with the pipe, a drain for the drum, deflector plates mounted in the drum and an air outlet pipe connected with the drum. 110 115

2. A humefier comprising a pipe adapted to direct a draft of air, means for injecting moisture into the same, a drum connected with the pipe, a drain for the drum, deflector plates arranged in cruciform relation and pivotally mounted in the drum and an air outlet pipe for the drum. 120

3. A humefier comprising a pipe adapted to direct a draft of air, means for injecting moisture into the same, a conical drum connected with the pipe, a drain for the drum, deflector plates mounted in the drum and an air outlet pipe connected with the drum. 125

4. A humefier comprising a pipe adapted to direct a draft of air, means for injecting 130

moisture into the same, a conical drum connected with the pipe, a drain for the drum, deflector plates mounted in the drum and arranged in cruciform relation, and an air 5 outlet pipe connected with the drum.

5. A humefier comprising a pipe adapted to direct a draft of air, means for injecting moisture into the same, a drum connected with the pipe, an outlet pipe connected with 10 the drum and a sieve adjustably mounted in the outlet pipe and adapted to be projected into the drum.

6. A humefier comprising a pipe adapted to direct a draft of air, means for injecting 15 moisture into the same, a drum connected with the pipe, a drain connected with the drum, deflector plates located in the drum, an outlet pipe connected with the drum, and a sieve movably mounted in the outlet pipe 20 and adapted to be projected into the drum.

7. A humefier comprising a pipe adapted to direct a draft of air, means for injecting

moisture into the same, a drum connected with the pipe, a drain for the drum, deflector plates movably mounted in the drum, an 25 outlet pipe connected with the drum and a sieve movably mounted in the outlet pipe and adapted to be projected into the drum.

8. A humefier comprising a pipe adapted to direct a draft of air, means for injecting 30 moisture into the same, a conical drum connected with the pipe, a drain for the drum, deflector plates pivotally mounted in the drum in cruciform relation, an outlet pipe connected with the drum and a sieve mov- 35 ably mounted in the outlet pipe and adapted to be projected into the drum.

In testimony whereof I affix my signature in presence of two witnesses.

VICTOR E. MERTZ.
